UNITED STATES PATENT OFFICE.

HARRY C. JOHANSEN, OF CHICAGO, ILLINOIS, ASSIGNOR TO SULLIVAN MACHINERY COMPANY, A CORPORATION OF MASSACHUSETTS.

LUBRICATING MECHANISM.

1,417,059.

Specification of Letters Patent. Patented May 23, 1922.

Application filed March 18, 1919. Serial No. 283,375.

To all whom it may concern:

Be it known that I, HARRY C. JOHANSEN, a citizen of the United States, residing at Chicago, in the county of Cook and State of Illinois, have invented certain new and useful Improvements in Lubricating Mechanism, of which the following is a full, clear, and exact specification.

This invention relates to lubricating mechanism for air and other gas compressors, and especially to mechanism for supplying lubricant to the cylinders of such compressors, although applicable, if desired, to lubricators for other parts of the compressor mechanism, 15 said invention being in the nature of a modification of or improvement on the lubricating mechanism shown and described in the application for Letters Patent filed by Halbert B. Halvorsen October 30, 1918, Serial 20 No. 260,306.

In the use of air and gas compressors, particularly in the case of large units or systems, it is customary to provide means for unloading the compressor at intervals to interrupt 25 the compressing action thereof without stopping the actuating motor or the compressor itself, said unloading means usually being controlled by the receiver pressure whereby when said pressure reaches a predetermined 30 maximum the compressor will be rendered temporarily inoperative, and when said receiver pressure falls below a predetermined minimum the compressor will be again rendered operative, thereby automatically 35 maintaining the receiver pressure between predetermined limits. Such compressors are usually provided with means for supplying lubricant to the cylinder or cylinders thereof, and it is found that when the compressor is running idly during the unloaded 40 periods a less quantity of lubricant is necessary than when the compressor is running loaded. The present invention has for its general object to provide means whereby the 45 quantity of lubricant supplied will be automatically controlled in accordance with the loaded or unloaded condition of the compressor, the supply being decreased or discontinued entirely when the compressor is 50 unloaded, thereby resulting in a greater economy in the use of lubricant and decreasing the difficulties due to the presence of excess lubricant in the compressor cylinders

and in the compressed air or other gas discharged therefrom.

The foregoing and other more particular objects of the invention, together with means whereby the same may be carried into effect, will best be understood from the following description of one form or embodiment thereof illustrated in the accompanying drawings. It will be understood, however, that the particular construction and arrangement described and shown has been chosen for illustrative purposes merely, and that the invention, as defined by the claims hereunto appended, may be otherwise practiced without departing from the spirit and scope thereof.

In said drawings,—

Fig. 1 is a side elevation of a compressor equipped with apparatus constructed in accordance with the invention.

Fig. 2 is an enlarged detail sectional view of a portion of the force feed lubricator and the controlling means associated therewith, the point of view being opposite that of Fig. 1.

Fig. 3 is a side elevation, partly broken away, of the parts shown in Fig. 2, the point of observation being to the right of the apparatus in Fig. 1.

Fig. 4 is an enlarged detail of parts shown in Fig. 3.

The invention is herein illustrated as applied to an angle compound compressor of well known type, the same comprising a low pressure cylinder 10 having an inlet 11 and a high pressure cylinder 12 having a discharge conduit 13, said cylinders having 90 interposed between them an intercooler 14 and being provided with pistons (not shown) operatively connected with a common crank shaft 15 provided with a flywheel or driving pulley 16.

As illustrative of means for unloading the compressor, there is herein shown an unloading valve 17 for controlling the flow of air through the inlet 11 to the low pressure cylinder 10, said unloading valve being preferably controlled through suitable means (not shown) by the receiver pressure or the pressure at the discharge side of the compressor. The details of the unloading valve and the means for controlling the same are not 105 shown and will not be described herein, as

such devices are well known in the art, may be of any usual or well known type, and specifically form no portion of the present invention.

5 Compressors of the type herein shown are usually provided with lubricating systems comprising separate mechanisms for supplying lubricant to the bearings and to the cylinders, respectively. As illustrative of 10 such a system, there is herein indicated at 18 a lubricant forcing device for supplying lubricant to the bearings and a separate lubricant forcing device 19 for supplying oil to the cylinders, the device 18 being actuated by a lever 20 connected by a link 21 with a crank disk 22 on the crank shaft 15, and the device 19 being provided with an operating arm 23 connected by a rod 24 with the lever 20. The lubricator 18 forms no 15 portion of the present invention and may be of any usual or well known type. Similarly, the lubricator 19 may be of any suitable character, but is herein illustrated as being of the well known McCord force feed 20 type, such as is usually connected through check valved pipes 19' with the cylinders of compressors of this character, and which is sufficiently well known not to require description in detail. For the purpose of the 25 present description it will be sufficient to say that said lubricator comprises a casing 25 (Figs. 2 and 3) containing suitable lubricant forcing and distributing means actuated from a shaft 26 provided with a ratchet 30 wheel 27 controlled by a holding pawl 28 and actuated by an operating pawl 29 carried by a swinging pawl carrier 30 actuated by the arm 23, whereby as said arm is oscillated by the rod 24 the shaft 26 will be intermittently rotated, thereby actuating the 35 lubricant forcing devices.

In accordance with the present invention, the operation of the lubricant forcing devices of the lubricator 19 is controlled by 40 means responsive to the loaded or unloaded condition of the compressor, by varying the operative engagement of the pawl 29 with the ratchet wheel 27. To this end, there is pivotally mounted on the shaft 26, 45 an arm 31 carrying a pawl shield 32 adapted, as said arm 31 is swung about the shaft 26, to be interposed between the pawl 29 and ratchet wheel 27 for a greater or less portion of the stroke of said pawl, and thereby 50 preventing engagement of said pawl with said ratchet during said portion of the stroke of the former. In this manner, the length of the operative stroke of the pawl, or the extent to which said pawl moves said ratchet 55 during each oscillation, may be varied, or said pawl may be held out of engagement with said ratchet throughout its stroke, thereby discontinuing the operation of the lubricating device altogether.

60 For controlling the position of the pawl

shield 32 in accordance with the loaded or unloaded condition of the compressor, there is provided a cylinder 33 bolted or otherwise secured to the top of the casing 25, said cylinder containing a piston 34 connected by a link 35 with the arm 31. The upper end of the cylinder 33 is connected by a pipe 36 with the intercooler 14, whereby the upper side of the piston 34 is subjected to the pressure in said intercooler. Beneath the piston 34 is a 70 spring 37 normally tending to move said piston upwardly against the pressure at the upper side thereof. The arrangement is such that as the piston 34 is moved downwardly by the intercooler pressure the pawl shield 32 will be moved into its inoperative position, and as said piston is moved upwardly to a greater or less extent by the spring 37, the pawl shield 32 will be moved into a position to interrupt the action of 75 the pawl 29 to a corresponding extent. The extent of upward movement of the piston 34 may be controlled, or said piston may be held against any upward movement at all, by means of an adjusting screw 38 having 80 threaded engagement with the upper head of the cylinder 33.

In the drawings the parts are shown in their normal position, wherein the pressure in the intercooler 14 is supplied through the 95 pipe 36 to the top of the piston 34, thereby holding said piston in its lowermost position against the tension of the spring 37, and holding the pawl shield 32 inoperative. When the unloading valve 17 is closed to unload the compressor, reciprocation of the piston in the high pressure cylinder 12 will result in the relief of the pressure in the intercooler 14, and even in the formation of a 100 partial vacuum therein. The pressure on the 105 upper side of the piston 34 being thus relieved, the spring 37 will move said piston upwardly, thereby moving the pawl shield 32 into operative position to interrupt or restrict the operation of the lubricator 19. 110

By the proper adjustment of the abutment screw 38, the amount of variation to which the operation of the lubricator is subjected upon the unloading of the compressor may be controlled. With said adjusting 115 screw in its uppermost position, as shown in Fig. 2, the spring 37 is permitted to move the piston 34 into its extreme uppermost position, so that when the compressor is unloaded the pawl shield 32 will be so moved 120 as to prevent any engagement of the pawl 29 with the ratchet 27 and thereby discontinue the operation of the lubricating device altogether. On the other hand, if the abutment screw 38 be moved downwardly to the 125 limit of its movement so as to engage the piston 34 when the latter is in its lowermost position, as shown in Fig. 2, any upward movement of the piston will be prevented so that the lubricator controlling device will be 130

rendered inoperative and the lubricator continue to operate in its normal manner irrespective of the loaded or unloaded condition of the compressor. By suitable adjustment of the screw 38 to an intermediate position, upward movement of the piston 34 may be arrested at any point to cause the pawl shield 32 to permit engagement of the pawl 29 with the ratchet wheel 27 through 10 any desired portion of the path of travel of said pawl.

From the foregoing, it will be seen that the present invention provides means whereby the amount of lubricant forced into 15 the compressor cylinder may be directly controlled by the loaded or unloaded condition of the compressor so as to be reduced when the compressor is running unloaded, or discontinued altogether during such un- 20 loaded period, as may be desirable in accordance with the requirements. These and other benefits and advantages of the invention will, however, be readily apparent to those skilled in the art.

25 What I claim as new and desire to secure by Letters Patent is:

1. The combination with a multiple cylinder compressor having an intercooler and provided with unloading means whose operation causes variation in intercooler pressure, of lubricating means controlled by the pressure in the intercooler.

2. The combination with a compressor, of lubricating means therefor, a ratchet connected with said lubricating means for operating the same, a pawl for actuating said ratchet, a pawl shield for controlling the engagement of said pawl with said ratchet, and means controlled by the loaded or un- 40 loaded condition of said compressor for controlling the position of said pawl shield.

3. The combination with a compressor, of lubricating means therefor, a cylinder, a piston therein operatively connected with said lubricating means for controlling the same, a spring cooperating with said piston at one side thereof, and means for subjecting the opposite side of said piston to variations in fluid pressure incidental to the loading and unloading of said compressor.

4. The combination with a multiple cylinder compressor provided with an intercooler, of lubricating means therefor, a cylinder, a piston therein operatively connected with said lubricating means for controlling the same, a spring cooperating with said piston at one side thereof, and means for subjecting the opposite side of said piston to the fluid pressure in said intercooler.

60 5. The combination with a compressor, of lubricating means therefor, pawl and ratchet mechanism for operating said lubricating means, means for varying the operation of said pawl and ratchet mechanism, a cylinder, a piston therein operatively connected

with said varying means, a spring cooperating with said piston at one side thereof, and means for subjecting the opposite side of said piston to variations in fluid pressure incidental to the loading and unloading of 70 said compressor.

6. The combination with a compressor, of lubricating means therefor, a ratchet connected with said lubricating means for operating the same, a pawl for actuating said 75 ratchet, a pawl shield for controlling the engagement of said pawl with said ratchet, a cylinder, a piston therein operatively connected with said pawl shield, and means for subjecting said piston to variations in fluid 80 pressure incidental to the loading and unloading of said compressor.

7. The combination with a multiple cylinder compressor provided with an intercooler, of lubricating means therefor, means 85 controlled by the fluid pressure in said intercooler for varying the operation of said lubricating means, and means adjustable to control the extent of variation thereof.

8. The combination with a compressor of 90 lubricating means therefor, a cylinder, a piston therein operatively connected with said lubricating means for varying the operation thereof, means for subjecting said piston to variations in fluid pressure incidental 95 to the loading and unloading of said compressor, and an abutment screw traversing the wall of said cylinder and adjustable from the outside thereof for limiting the movement of said piston.

9. The combination with a compressor of lubricating means therefor, a cylinder, a piston therein operatively connected with said lubricating means for varying the operation thereof, a spring cooperating with 100 said piston at one side thereof, means for subjecting the opposite side of said piston to variation in fluid pressure incidental to the loading and unloading of the compressor, and an abutment member adjustable 105 from outside said cylinder for limiting the movement of said piston.

10. The combination with a compressor, of lubricating means therefor, a cylinder, a piston therein operatively connected with 115 said lubricating means for varying the operation thereof, a spring cooperating with said piston at one side thereof, means for subjecting the opposite side of said piston to variations in fluid pressure incidental to the 120 loading and unloading of said compressor, and an abutment screw in threaded engagement with said cylinder for limiting the movement of said piston.

11. The combination with a multiple cylinder compressor provided with an intercooler, of lubricating means therefor, means for varying the operation of said lubricating means, a cylinder, a piston therein operatively connected with said varying means 125

- for operating the same, and means for subjecting said piston to the fluid pressure in said intercooler.
12. The combination with a multiple cylinder compressor provided with an intercooler, of lubricating means therefor, a ratchet connected with said lubricating means for operating the same, a pawl for actuating said ratchet, a pawl shield for controlling the engagement of said pawl with said ratchet, a cylinder, a piston therein operatively connected with said pawl shield, a spring cooperating with said piston at one side thereof, means for subjecting the opposite side of said piston to the fluid pressure in said intercooler, and an abut-
- ment screw in threaded engagement with said cylinder for limiting the movement of said piston.
13. The combination with a multi-cylinder compressor provided with an intercooler, driving means for said compressor, and means for discontinuing the compressive action of said compressor without interrupting the driving thereof by said driving means, of lubricating means for said compressor and means for controlling the operation thereof controlled by pressure conditions in said intercooler. 20 25

In testimony whereof I affix my signature.

HARRY C. JOHANSEN. 30
